UNITED STATES PATENT OFFICE

2,438,788

PAPER BOX FORMING APPARATUS

Frank D. Palmer, Chicago, Ill., assignor to F. D. Palmer, Inc., Chicago, Ill., a corporation of Illinois

Application August 11, 1944, Serial No. 549,030

2 Claims. (Cl. 93—51)

1

This invention relates to an improved paper box forming method and apparatus, and has particular reference to paper box forming machines of the type in which a reciprocating plunger moves through a die and through other elements of apparatus for forming a box from a pre-cut blank.

The main objects of the invention are to provide a reciprocating plunger-type machine wherein the productive capacity is greatly increased over that of conventional machines of the type mentioned; to provide a reciprocating plunger type of machine wherein box members may be made in pairs to constitute, for example, a telescopic box and cover packaging unit, or by which boxes of one size or of two different sizes may conveniently be made while operating the machine; and, in general, it is the object of the invention to provide improved box-making equipment of the character indicated.

Other objects and advantages of the invention will be understood by reference to the following specification and accompanying drawings (two sheets), wherein there is illustrated a box-making machine embodying a selected form of the invention.

In the drawings:

Fig. 1 is a plan of a paper board blank adapted to be formed into a box by the apparatus herein disclosed;

Fig. 2 is a perspective of a partially completed box made from the blank shown in Fig. 1;

Fig. 3 is a plan of another blank substantially similar to that shown in Fig. 1, which is also adapted to be formed into a box by the disclosed equipment;

Fig. 4 is a perspective illustrating a partially completed box formed from the blank shown in Fig. 3;

Fig. 5 is a more or less diagrammatic illustration of the principal elements of a reciprocating plunger-type box-forming machine embodying my improved construction;

Fig. 6 is a section on the line 6—6 of Fig. 5; and

Fig. 7 is a section corresponding to Fig. 6 but showing a changed position of the parts.

The apparatus selected for illustration in this application comprises a carton blank feeding conveyor 1, which is arranged to feed carton blanks, such as represented at 2a and 2b to a table or plate 3 and against a stop 4 carried by said plate 3. The plate 3 has an opening 5 therein through which a vertically reciprocable plunger 6 is mov-

2

able for forming the blanks 2a and 2b respectively, into boxes.

The plunger 6 is vertically slidably mounted in any suitable manner, for example, by means of a cross arm 7, which extends transversely through approximately the center of the plunger 6. The cross arm 7 may be of double bar formation, as indicated in Fig. 5, and provided with single bar end portions 8 which extend between 10 pairs of guides 9 at each side of the machine. The outer ends of the single bar portions 8 may be suitably formed to co-operate with the forked ends 10 of levers or arms, such as shown at 11. The arms 11 are adapted to be rocked about 15 fixed pivots by means of rotary cams, such as shown at 12, acting through rock arms such as shown at 13 and suitable connections illustrated in Fig. 5, to the arms 11.

As shown in Fig. 5, the plunger 6 is in its 20 lowered position and a blank 2b is in position on the plate 3 over the opening 5. The next movement of the plunger 6 will be in an upward direction, and the upper end 14 of the plunger will move upwardly through the opening 5 in the plate 25 and press the box blank 2b through folders in the form of rollers 15—15, which operate to turn the side walls 16 of the blank downwardly relative to the top wall 17, as shown in Fig. 4. Continued upward movement of the plunger and box 30 blank 2b carries the blank through the zone of operation of tuckers, such as represented at 18—18, which are operated as usual to fold inwardly the end ears 19 of the side walls. Continued movement upwardly of the plunger next 35 passes the upper end portion of the plunger and the partially formed box thereon between suitable devices for folding the end walls 20—20 downwardly into overlapping relation to the end flaps 19, to thereby complete the formation of the box 40 or cover element. The means for folding the end walls 20 downwardly may consist of separate folding and pressing means, or such folding and pressing means may be combined into a single unit, such as represented by the rotatable end 45 wall pressing drums represented at 21—21. The drums 21—21 are suitably rotatably mounted, and they may be driven in timed relation to the movement of the plunger 6 or they may be driven by the plunger. For the latter purpose, the end 50 folding and pressing drums 21 may each be equipped with a series of arms such as represented at 22, which are provided with rollers on their outer ends for engagement with the upper end of the plunger 6. Such engagement of the 55 rollers 22 by the plunger 6 on its upward move-

ment serves to rotate the respective drums 21 in such a direction that pressure pad portions 23 thereon will act against the box ends 20 to fold them down and press them tightly against the underlying end flaps 19-19. The end flaps 19-19 may have previously been coated with suitable adhesive so that the end walls 20-20 will be adhesively secured to said end flaps 19 in folded box-forming condition.

After the plunger 6 has reached its uppermost position, substantially as represented in Fig. 7, it next begins to move downwardly. As an incident to such downward movement, the box section 24b is stripped from the plunger and discharged to a conveyor 25, which serves to conduct the box out of the machine and to some other place for subsequent operations. The stripping means may be considerably varied and is here represented as embodying a fixed stripper member 26 and a movable stripper member 27. The stripper member 27 is made movable so that after the box is released from the upper end of the plunger 6, the stripper member may move laterally to discharge the box to the conveyor 25. For that purpose, the stripper member 27 is illustrated as being carried by a movable member 28, which is supported by a pair of links 29 for lateral movement. The stripper member 27 is so constructed as to provide an upstanding member 30 which will engage and push the box 24b laterally over the upper edge of the stripper 26 and to the conveyor 25. Suitable means (not shown) are, of course, provided for actuating the stripper member 27 in synchronized relation to the movements of the plunger 6.

Upon downward movement of the plunger 6 from its elevated position, as shown in Fig. 7, the lower end portion 31 thereof will engage a blank 2a which has by that time been delivered against the stop 4 and over the opening 5 in the plate. Continued downward movement of the plunger forces the box blank 2a between side folders, such as represented at 32, tuckers represented at 33, and end wall folders and pressers, such as represented at 34. These parts operate on the box blank 2a in the same manner that the corresponding upwardly disposed parts act on the box blank 2b. Stationary or spring-acting stripper members 35 are provided for the purpose of stripping the box 24a from the lower end of the plunger when the latter begins its next upward movement. The boxes 24a thus removed from the lower end of the plunger, are delivered to a conveyor 36 which carries the boxes to the desired place.

The box members 24a and 24b may be of exactly like size and construction, or one box may be sufficiently larger than the other to provide a telescopic fit of the larger box over the side and end walls of the other box. In this instance, the boxes formed by the opposite ends of the plunger are of like size. If it is desired to produce a larger box on one end of the mandrel or plunger, that end of the plunger will, of course, be enlarged to the desired inside dimensions of the larger box, and the folding elements which co-operate with such enlarged end of the mandrel will, of course, be appropriately located or adjusted.

When the box blank 2b is moved upwardly, its side wall elements are folded downwardly relative to its central or top wall-forming panel 17, and adhesive is applied to the upper side of the side wall end ears 19, as represented in Fig. 3. In this arrangement, the end wall 20, when folded downwardly, will engage the adhesive-carrying surfaces of the end flaps 19.

When the box blank 2a is formed into a box by the described apparatus, its side and end walls 16 and 20 will be folded upwardly relative to its central or bottom panel 17. In that case, if adhesive were applied to the upper surfaces of the end flaps 19, they would have to be folded inwardly after the end flaps 20 are folded upwardly in order to effect engagement of the adhesive bearing surfaces of the end flaps 19 with the outside surface of the end walls 20. This would result in a slightly different forming of the box, and is otherwise undesirable.

In order that the end walls 20 may be folded into outwardly overlying relation to the end flaps 19, adhesive is applied to the upper surfaces of the end flaps 20 of the blank 2a, as indicated by the stippling in Fig. 1. Then, when the end wall 20 is folded upwardly, its upper adhesive surface is folded into engagement with the outside surfaces of the end flaps 19, to which it becomes adhesively united in substantially the same relationship that exists between the end wall and end flaps of the box formed from the blank 2b.

For the purpose of applying adhesive alternately to the end flaps 19 of the blanks 2b, and to the end walls 20 of the blanks 2a, a pair of glue-applying devices 37 and 38 are provided. The adhesive-applying device 37 may be arranged to apply adhesive to the upper surfaces of the end flaps 19 of the blank 2b, and the adhesive-applying device 38 may be arranged to apply adhesive to the upper surfaces of the end wall portions 20 of the blanks 2a. In the arrangement illustrated, adhesive is applied to upper surface portions of both blanks, but it will be apparent that, if desired, the adhesive-applying unit 37 may be replaced by one which operates to apply adhesive to the underside of the end wall 20 of the blanks 2a. Such an arrangement is perhaps less desirable than the first-described arrangement in that it involves certain problems of keeping the adhesive-carrying under-surface out of contact with the conveyor 1, or other elements of the mechanism.

It will be seen that the described mechanism employs the movement in each direction of the reciprocating plunger to form a box. In conventional reciprocating plunger type mechanisms, which have been known for many, many years past, boxes are formed only on the down-stroke of the plunger, and the up-stroke thereof has been wasted return movement.

By the described improvement, the capacity of a reciprocating plunger type mechanism is substantially doubled, and the machine is provided with the capacity of simultaneously making two different sizes of boxes. The two sizes of boxes formed may be related so that one constitutes a telescopic cover for the other, or they may constitute wholly unrelated, differently sized box units.

Various changes in the apparatus and in the particular elements for co-operating with the plunger to fold the box blanks may, of course, be made, while retaining the benefits of the described construction.

I claim:

1. In a paper box making machine, means for successively delivering box blanks to a predetermined box position, a double-ended plunger, means for reciprocating said plunger so as to cause its opposite ends to successively traverse said box blank position, and a pair of box-forming devices respectively disposed on opposite sides of said box blank position and respectively

cooperating with the opposite ends of said plunger for forming boxes on said plunger ends incident to movement of the plunger in opposite directions.

2. In a paper box making machine, means for successively delivering box blanks to a predetermined box position, a double-ended plunger, means for reciprocating said plunger so as to cause its opposite ends to successively traverse said box blank position, a pair of box-forming devices respectively disposed on opposite sides of said box blank position and respectively cooperating with the opposite ends of said plunger for forming boxes on said plunger ends incident to movement of the plunger in opposite directions, said box blank delivering means being arranged to feed all of said blanks through the same path of travel from one side of said box blank position, and a pair of adhesive applying devices arranged to respectively apply adhesive to predetermined areas of alternate blanks being fed through said path of travel.

FRANK D. PALMER.
